(57) CLAIM

The ornamental design for a spatula, as shown and described.

DESCRIPTION

FIG. 1 is a perspective view of a spatula showing our new design;

FIG. 2 is a side view thereof, the opposing side being a mirror image;

FIG. 3 is a front view thereof;

FIG. 4 is a rear view thereof;

FIG. 5 is a top view thereof; and,

FIG. 6 is a bottom view thereof.

The broken lines shown in the drawings are included for purposes of illustrating portions of the spatula and form no part of the claimed design.
